UNITED STATES PATENT OFFICE.

SAMUEL COLEMAN ADLER, OF PHILADELPHIA, PENNSYLVANIA.

DESIGN FOR SOAP.

SPECIFICATION forming part of Design No. 16,928, dated October 12, 1886.

Application filed August 30, 1886. Serial No. 212,264. Term of patent 7 years.

To all whom it may concern:

Be it known that I, SAMUEL COLEMAN ADLER, a citizen of the United States, residing at Philadelphia, in the county of Philadelphia and State of Pennsylvania, have invented and produced a new and original Design for Cakes of Soap, of which the following is a specification, reference being had to the accompanying drawings, forming part thereof.

Figure 1 is a perspective view of my newly-designed cake of soap. Fig. 2 is a sectional view thereof on the line $x x$. Fig. 3 is a sectional view thereof on the line $y y$, these three views fully illustrating my design.

The feature of my design consists in a bevel on each of the edges of a parallelopiped cake of soap.

A A represent the upper and lower opposite flat surfaces of the cake, a a the opposite side planes, and b b the end faces thereof, the

respective members, as shown by the similar indicating-letters, being parallel to each other.

c c c represent oblique lines forming bevels, which cut off all the edges where the upper and lower surfaces respectively meet the side planes and end faces, and where the side planes and end faces respectively conjoin, and all of which lines of conjunction would otherwise on an ordinary parallelopiped be rectangular.

30

I claim—

The design for a cake of soap, as herein shown and described, the same consisting of a parallelopiped having beveled edges where the respective surfaces, side planes, and end faces 35 conjoin.

SAMUEL COLEMAN ADLER.
